United States Patent Office.

CHENEY KILBURN, OF PHILADELPHIA, PENNSYLVANIA, ASSIGNOR TO
KILBURN & GATES, OF SAME PLACE.

Design No. 4,352, dated September 13, 1870.

DESIGN FOR THE BOXES FOR THE TOPS OF BUREAUS.

The Schedule referred to in these Letters Patent and making part of the same.

I, CHENEY KILBURN, of Philadelphia, county of Philadelphia, State of Pennsylvania, have invented or produced a Design for Boxes for the Tops of Bureaus, of which the following is a specification.

This design, which is for the shape of a box of the kind usually secured to the tops of bureaus, consists, mainly, of a rectangular box with a projecting front, having prominent corner pieces, the whole, when finished with appropriate moldings, forming a box of ornamental appearance.

On reference to the drawing—

Figure 1 represents a perspective view of a box made in accordance with my design, and

Figure 2, a plan view of the box in outline.

The body A of the box is rectangular, or oblong; and at the front of the same there is a projecting portion, B, the latter being perfectly plain, or having

prominent corners, *c c*, as represented in the drawing, or being otherwise ornamented.

The molding or finish for the edge of the box, of whatever character employed, is carried entirely around the projection B, as shown in fig. 1.

I claim—

The design for boxes for the tops of bureaus, substantially as described and as represented in and by the accompanying drawing.

In testimony whereof I have signed my name to this specification in the presence of two subscribing witnesses.

CHENEY KILBURN.
